UNITED STATES PATENT OFFICE.

LUTHER L. KNOX, OF PITTSBURG, PENNSYLVANIA, ASSIGNOR OF ONE-FOURTH TO MONT MURRAY AND ONE-FOURTH TO H. E. WEISKOPF, OF PITTSBURG, PENNSYLVANIA.

WATER-COOLED FURNACE-DOOR.

SPECIFICATION forming part of Letters Patent No. 789,549, dated May 9, 1905.

Application filed March 7, 1903. Serial No. 146,631.

To all whom it may concern:

Be it known that I, LUTHER L. KNOX, of Pittsburgh, Allegheny county, Pennsylvania, have invented a new and useful Water-Cooled Furnace-Door, of which the following is a full, clear, and exact description, reference being had to the accompanying drawings, forming part of this specification, in which—

Figure 1 is a front elevation showing one form of my improved door. Fig. 2 is a vertical cross-section. Fig. 3 is a horizontal cross-section, and Fig. 4 is a partial horizontal section showing a modified form.

My invention relates to the class of water-cooled doors for furnaces, such as open-hearth furnaces, heating-furnaces, &c., and is designed to provide an improved construction which will be long-lived, which will prevent the formation of steam-pockets, and which may be cheaply made and repaired.

In the drawings, referring to the form of Figs. 1, 2, and 3, I show the body of the door 2 as formed of a hollow casting which is integral with the hollow side cheeks 3. The side cheeks have diverging side walls, as shown at 4, in order to better hold the refractory material, which is filled in back of the body and between these cheeks. The casting is open at its top and is preferably provided with a shoulder or inset portion 5 in its rear wall to receive the flanged portion 6 of a top cross-rail 7, which is secured by bolts 8. The rail 7 and the body may be provided with lugs 9, arranged in pairs and perforated for attaching to the means for raising and lowering the door. The lower face of the rail 7 is preferably inclined downwardly and rearwardly, as shown at 10. At the lower end of the body-casting I preferably provide forwardly-projecting cast flanges 11 at opposite sides, which are bolted to corresponding flanges 12, cast integrally with the door-sill 13. This sill is cast in the form of a hollow closed box with the inner surface or roof of its top inclined upwardly from the back toward the front, as shown at 14. This surface is also preferably inclined upwardly in

opposite directions from the center of the casting toward the outlets and from the ends upwardly and inwardly toward the outlets, 50 as indicated by the dotted lines in Fig. 1. The object of these inclined inner faces is to prevent the forming of steam-pockets and to carry any steam which collects toward the outlets for the water from this sill. The 55 front of the sill is provided with two cleaning-openings, which are closed by screw-plugs 15. The top of the sill is flat to fit against the lower face of the body-casting, the rear portion of this face being inclined upwardly, as 60 shown at 16. The water-supply pipe 17 preferably leads downwardly through the hollow body at one front corner, as shown in Fig. 3, and projects through registering holes into the hollow sill. From this sill the water 65 flows through U-shaped pipes 18 into the hollow body and cheeks and circulates therein, the overflow being taken off through the pipe 19, which may be set at any desirable level at or near the upper end of the door. I prefer- 70 ably provide a peep-hole 20 by coring the casting, suitable guides 21 being provided above and below it to receive the closing-plate.

Instead of forming the side cheeks of the 75 door hollow and integral with the body I may form them separately and secure them to the body. Thus in Fig. 4 I show the hollow body 2' as having a lateral flange 22, the side cheek 3' being a separate casting or member having, preferably, the inner inclined face 4' and provided with a flange 23, which is bolted to the flange 22.

The advantages of my invention result from the simplicity and cheapness of the 85 door, its long life, and the avoiding of steam-pockets. The cast construction gives the door great strength, and it is not liable to crack.

The door may be made of shapes without 90 casting, and the parts may be varied without departing from my invention.

I claim—

1. A water-cooled furnace-door having a

hollow body with a flange at its bottom which projects forwardly in front of said body, a separate hollow sill secured to the body by a bolt extending through the flange and means for circulating water through the sill and body; substantially as described.

5 2. A door having a hollow water-cooled sill with an upper outlet, the roof of the sill being inclined to direct steam-bubbles toward said outlet; substantially as described.

10 3. A door having a hollow water-cooled sill with opposite outlets connecting with the door, the roof of the sill being oppositely inclined from the center toward said outlet; substantially as described.

15 4. A furnace-door having a hollow cast body provided at its bottom with flanges projecting forwardly in front of the body, a hollow cast sill having front projecting flanges removably bolted to the body-flanges, said securing means being accessible when the door is in place, and external front pipes connecting the body and sill; substantially as described.

20 5. A hollow water-cooled door having hollow side cheeks, a hollow sill extending the entire width of the door and removably secured thereto, and pipes for circulating cooling fluid through the sill, the door and the cheeks; substantially as described.

25 6. A hollow furnace-door having hollow side cheeks, and a hollow lower sill removably secured to the body, and pipes for circu-

lating fluid through the sill, the body and the side cheeks; substantially as described.

35

7. A hollow water-cooled furnace-door having a vertical back plate, and an inner transverse top sill removably secured to the door by bolts extending through its back plate and terminating within the hollow water-containing cavity of the door; substantially as described.

8. A furnace-door having a hollow body with bottom flanges projecting forwardly in front of the body, a hollow cross-sill removably bolted to said front flanges, external pipe connections between the sill and body, and a removable top sill secured to the inner portion of the body by bolts extending through the back plate of said body; substantially as described.

40

9. A hollow water-cooled door having an open top, a hollow sill secured to the lower part of the door, and having outlet-pipes leading to the hollow door, the sill being arranged to direct any steam to said connecting-pipes, and means for circulating a cooling fluid through the door and sill; substantially as described.

45

50 In testimony whereof I have hereunto set my hand.

60 LUTHER L. KNOX.
